United States Patent Office

Des. 193,944
Patented Oct. 30, 1962

193,944

FOOD MIXER OR THE LIKE

Robert O. Ernest, Oak Park, and Jerold R. Peterson, Roselle, Ill., assignors to Sunbeam Corporation, Chicago, Ill., a corporation of Illinois

Filed Jan. 24, 1962, Ser. No. 68,508

Term of patent 14 years

(Cl. D44—1)

FIG. 3.

FIG. 4.

FIG. 5.

FIG. 6.

FIG. 1 is a perspective view of a food mixer or the like embodying our new design, with beaters shown illustratively in broken lines;

FIG. 2 is a side elevational view thereof;

FIG. 3 is a top plan view;

FIG. 4 is a bottom plan view;

FIG. 5 is a front elevational view; and

FIG. 6 is a rear elevational view.

The essential features of our food mixer are shown thereon in full lines.

We claim:

The ornamental design for a food mixer or the like substantially as shown and described.
